AIR WASHER

Edward K. Wills and James H. McElhannon,
Corpus Christi, Tex.

Application May 28, 1935, Serial No. 23,920

1 Claim. (Cl. 261—116)

This invention appertains to new and useful improvements in air washers adapted for use in conjunction with internal combustion engines, the same being an improvement on our co-pending application Serial No. 740,345, filed August 5 17, 1934.

The principal object of the present invention is to provide an air washer employing a moistening medium to promote eradication of foreign matter before delivery to the engine with which 10 it is being employed.

During the course of the following specification, other important objects and advantages of the invention will become apparent to the reader.

15 In the drawings:

Figure 1 represents a side elevational view of the air washer shown installed with an engine.

Figure 2 is a fragmentary top plan view of the washer.

20 Figure 3 is a fragmentary longitudinal sectional view through the manifold of the washer.

Figure 4 is a vertical sectional view taken substantially on line 4—4 of Figure 2.

Figure 5 is a fragmentary horizontal sectional 25 view taken substantially on line 5—5 of Figure 4.

Figure 6 is a cross sectional view taken substantially on line 6—6 of Figure 2.

Referring to the drawings wherein like numerals designate like parts, it can be seen that 30 numeral 5 generally refers to a Diesel type of engine with air intake ports 6. The present invention employs an elongated manifold pipe 7 from which the spout 8 extends to engage into the air inlet port 6 of the engine, each spout 8 being provided with an upstanding lip 9 to limit the engagement of the spout into the port.

The washer consists of a rectangular (or any other decided shape) shaped casing 10, the interior of which is divided by a transverse partition 11 merging as at 12 with a horizontal partition 13, these partitions defining a chamber 14 with which and through the wall of the casing the manifold pipe 7 communicates.

Depending into the casing 10 through the top 45 thereof is the stack 15 terminating at its lower end in spaced relation to the bottom of the casing and extending for a substantial distance at its upper end above the top of the casing. Extending into the stack 15 through the upper ex-

ternal portion thereof is the water conduit 16 which makes connection as at 17 in the stack with the depending tube 18 terminating in a spray nozzle 19 located a substantial distance upwardly from the lower end of the stack. 5

A large bulbular mesh enclosure 20 is mounted at the upper end of the stack 15 and through this air must be drawn. Numeral 21 represents a drain pipe for the lower portion of the casing 10.

It can now be seen that when the motor 5 is 10 in operation, air is sucked through the mesh 20 which removes all large foreign particles and as this air is drawn downwardly through the stack 15 it is treated by the spray from the nozzle 19.

This dampening or moistening of the air will 15 obviously cause a precipitation of all residual foreign matter to the bottom of the casing where it can be drained off through the pipe 21. The remaining air passes upwardly in a direction following the arrows in Figure 4 and out into the 20 manifold pipe 7 from where it is taken by the engine 5.

While the foregoing specification sets forth the invention in specific terms, it is to be understood that numerous changes in the shape, size, and 25 materials may be resorted to without departing from the spirit and scope of the invention as claimed hereinafter.

Having described the invention, what is claimed as new is:

An air washer for engine comprising a casing, a transverse vertical partition disposed substantially intermediately across interior of the casing, a horizontal partition in the casing with which the vertical partition merges to define a 35 chamber, said vertical partition terminating adjacent to the top of the casing, a discharge pipe communicating with the interior of the casing at the chamber, a narrow inlet tube depending into the casing from the top thereof, said tube 40 being provided with an air filter at the top thereof, the upper portion of the tube projecting above the top of the casing, a fluid conduit extending into the tube at the portion above the top of the casing, and a downwardly disposed nozzle at the 45 inner end of the conduit.

EDWARD K. WILLS.
JAMES H. McELHANNON.
